United States Patent Office.

H. P. CONANT, OF BOSTON, MASSACHUSETTS.

Design No. 2,935, dated February 18, 1868.

DESIGN FOR A HAT-RACK.

The Schedule referred to in these Letters Patent and making part of the same.

TO ALL WHOM IT MAY CONCERN:

Be it known that I, H. P. CONANT, of Boston, in the county of Suffolk, and State of Massachusetts, have invented or produced a new and useful Design for a Hall or Hanging Hat-Tree, of which the following is a full, clear, and exact description, reference being had to the accompanying drawings, making a part of this specification, in which—

Figure 1 represents a front view of my design, and

Figure 2 a vertical transverse section of the same.

The nature of my invention or design consists of a hat-rack or tree to be attached or hung to the wall of a hall or entry, or other desirable place, and made of a frame enclosing a glass or mirror, all of a diamond or lozenge-shape.

In the drawings, A represents the moulded outer portion of the frame, provided with pins or projections *a*, for hanging hats, clothes, or other articles upon. B is a plane surface of the frame, and C is a bead, surrounding the glass or mirror D; the whole, as viewed from the front, being of a diamond or lozenge-shape.

What I claim as my invention, and desire to secure by Letters Patent, is—

The new and original design for a hanging hat-rack or tree, as set forth, the same consisting of a frame and glass or mirror of a diamond or lozenge-shape, as shown.

In testimony whereof, I have signed my name to this specification in the presence of two subscribing witnesses.

H. P. CONANT.

Witnesses:

J. H. ADAMS,

M. S. G. WILDE.
